[57] CLAIM

The ornamental design for a table A-frame for a booth seating system, or the like, substantially as shown and described.

DESCRIPTION

FIG. 1 is a top plan view of the table A-frame for a booth seating system, or the like, and showing my new design;

FIG. 2 is a side elevational view thereof, the opposite side being the mirror image thereof;

FIG. 3 is a left side elevational view thereof; and

FIG. 4 is a right side elevational view thereof.

The bottom side of the table A-frame is plain and unornamental.

*FIG. 1.**FIG. 2.**FIG. 3.**FIG. 4.*
